APPARATUS FOR DRILLING LATERAL BORES
DEVIATING FROM VERTICAL WELL BORES

John A. Zublin, Los Angeles, Calif.

Application October 11, 1950, Serial No. 189,591

6 Claims. (Cl. 255—1.6)

1

The present invention relates to novel apparatus for drilling lateral bores deviating from existing vertical well bores.

This application is a continuation-in-part of my application Serial No. 64,524, filed December 10, 1948.

It is a purpose and object of the invention to provide a combination unit susceptible of being assembled at the well surface and attached as a complete operative unit to the lower end of a conventional rotary drill string to be lowered into an existing well, oriented and operated to effect drilling of a lateral bore by rotation of the conventional drill string pursuant to normal rotary drill practice.

More specifically, it is an object of the invention to provide a self-contained unit embodying a normally curved resilient flexible drill guide susceptible of being flexed to a lesser curvature, a flexible drill bit driving member disposed interiorly of the drill guide for free rotation therein and clutch means operative to permit free rotation of the drill bit while the flexible resilient normally curved drill guide is held against rotation by frictional engagement with the existing well bore and engageable to permit limited rotation of the curved resilient drill guide within the vertical well bore for purposes of orientation.

The art of drilling lateral bores deviating from an existing vertical well bore is not unknown and is the subject matter of several prior U. S. patents issued to me, examples being U. S. Patents Nos. 2,336,338, 2,344,277 and 2,382,933. The present invention is addressed to a specifically improved combination unit that is highly effective in the drilling of lateral bores from existing vertical well bores and which is especially well adapted for application to a conventional rotary drill string for operation through the medium of well-accepted rotary drilling practices.

A preferred embodiment of the invention is illustrated in the accompanying drawings in which

Figure 1 is a side elevation of the combination unit of the invention showing the same in the position occupied thereby when inserted into a vertical well bore ready to initiate the drilling of a lateral bore.

Figure 2 is a detailed cross-sectional view through the combination unit illustrating details of the clutching arrangement and showing the clutch elements disengaged.

Figure 3 is another detailed view similar to Figure 2 but illustrating the clutch elements in engaged position.

2

Figure 4 is a detailed view partially in cross section, showing the manner of attachment of the bit to the driving member, and the manner of mounting the flexible driving member within the resilient normally curved guide.

Referring to Figure 1, reference character 10 designates the lower end of the lowermost section of a conventional substantially non-resilient tubular drill string. It will be understood that 10 the drill string is made up of numerous pipe sections usually approximately 30 feet in length and extends downwardly from the surface of the well.

In Figure 1 the combination unit constituting 15 the present invention is illustrated as being just introduced to the vertical well bore 11. The combination unit embraces an upper flexible non-resilient tubular drill string section 12 which preferably takes the form of the non-resilient 20 sectional flexible metallic drill pipe more particularly disclosed in my prior U. S. Patent 2,515,366 issued on July 18, 1950. Reference to that patent will indicate that the metallic sections which are interconnected by dovetailed slots 25 are susceptible of relative limited axial movement permitting a substantial movement of the upper end of the flexible drill string section 12. It will be understood that the combination unit of the present invention may, depending upon the 30 length of the deviating bore to be drilled, embrace more than one section of non-resilient flexible pipe 12. The lower end of the flexible non-resilient drill string section 12 carries what for convenience is herein termed a sub 13. An impervious, preferably rubber, tubular liner 14 extends substantially from end to end of the flexible 35 drill string section 12 being secured in place therein by a combined threaded and riveted connection indicated at 15 in Figure 2. It will be understood that the upper end of the flexible 40 tubular drill section 12 carries a complementary coupling member for attachment to the lower end of the lower section of the drill string 10 and that the upper end of the rubber tubular member 14 is attached to the upper end of the 45 flexible drill string section 12 by a connection similar to that shown at 15 in Figure 2.

The sub 13 threadedly receives the upper end of the tubular coupling member 16. The lower end of the tubular coupling member 16 is threadedly secured to the upper end of a second flexible tubular bit driving member 17 of somewhat less diameter than the flexible tubular drill string section 12 but otherwise of the same construction. The arrangement is such that the flexible 50 tubular drill string section 12, the tubular cou-

pling member 16 and the flexible tubular member 17 rotate in unison. The drill bit 18 is carried at the extreme lower end of the flexible tubular member 17 in a manner which will be presently described so that upon rotation of the drill string including the lower portion of the lower section 10 thereof, the flexible tubular drill string section 12, the coupling member 16 and the tubular bit driving member 17, the bit 18 is positively driven by a direct drive through the drill string extending to the surface of the well. No inner driving member is required.

Surrounding the tubular flexible drive member 17 and substantially coextensive in length therewith is the flexible resilient normally curved drill guide or deflector tube 19 which, when in the position shown in Figure 1, has been flexed to a considerably lesser curvature than that which it would assume under normally unstressed conditions. This normally curved flexible resilient drill guide 19 is preferably of the type disclosed in my prior U. S. Patent 2,515,365 issued July 18, 1950. This normally curved resilient drill guide is formed of tubular metal pipe having a slot through the wall thereof extending in a generally helical path along and around the pipe. The sides of the slot are provided with inter-meshing and inter-locking dovetailed teeth. The normally curved resilient drill guide 19 will be provided with a normal curvature in unstressed condition that approximates the curvature at which a deviating drain hole to be drilled thereby will assume.

By way of illustration, it is advantageous to employ flexible curved resilient drill guides such as 19 which have an over-all length of about 16 feet and a curvature in the unstressed condition that lies on a radius of about 16 feet. Under such conditions, the height of the arc formed by the guide when in unstressed condition will be found to be about 30 inches. When such a drill guide is inserted into a well bore, depending somewhat on the diameter of the well bore, the lower end of the drill guide will be forced against the side wall of the vertical bore under a pressure of the order of from 100 to 700 pounds.

The normally curved flexible drill guide 19 has no direct connection to the other elements of the combination unit of the present invention. In fact, the flexible non-resilient tubular drive member 17 is mounted to rotate freely within the normally curved resilient flexible drill guide 19 in all permissible degrees of curvature thereof. To this end anti-friction bearings 20, 21, 22 and 23 are interposed between the normally rotating elements of the unit and the normally non-rotating curved resilient drill guide 19.

Returning to the discussion of the manner of attaching the bit 18 to the lower end of the flexible non-resilient tubular drive member 17, it will be noted that the bit 18 is received in a tubular coupling member 24 which has a neck of reduced diameter 25 to the upper end of which the lower end of the flexible tubular drive member 17 is threaded secured. The lower end of the normally curved flexible resilient drill guide 19 is threaded connected to a short annular bearing member 26 which provides a seat for the anti-friction bearing rollers 23 and which, at its lower end, is adapted to ride upon the ball bearings 27 which lie between the annular member 26 and the shoulder 28 of the coupling member 24 for the bit 18. A second set of ball bearings 29 lie between the upper end of the annular member 26 and the extreme lower end of the tubular flexible

drive member 17. The arrangement is such that upon rotation of the tubular drive member 17 little or no rotational force is imparted to the normally curved flexible resilient drill guide 19. The tubular flexible drive member 17, similarly to the tubular flexible drill string section 12, is provided with an impervious tubular liner, preferably of rubber, 30 secured at its opposite ends to the tubular flexible drive member 17 through combined thread and rivet connections such as indicated at 31, Figure 4.

Referring to Figure 2, it will be observed that the upper end of the normally curved resilient flexible drill guide 19 threadedly receives and carries a short annular bearing member 32 providing a seat for the anti-friction bearing rollers 29 and which is provided with a ball race 33 on which the ball bearings 34 ride. The tubular coupling member 16 extends through the annular bearing member 32 and is free for axial movement therein. It will thus be seen that the normally curved resilient drill guide 19, together with the lower annular bearing member 26 and the upper annular bearing member 32 constitutes a unitary structure within which the tubular coupling member 16, the flexible tubular drive member 17 and the reduced neck 25 of the bit coupling member 24 are adapted to freely rotate when the clutch means presently to be described is disengaged for drilling purposes.

Coming now to the clutch means of the combination unit which constitutes an important feature of the present invention, it will be observed that the annular bearing member 32 which as stated is integrally assembled with the normally curved resilient drill guide 19 carries a semi-circular downwardly extending clutch tooth 35 and that the upper end of the tubular flexible drive member 17 carries a complementary semi-circular clutch tooth 36. The clutch teeth 35 and 36 are shown in disengaged position in Figure 2. In this position, the coupling member 16 and the inner flexible tubular drive member 17 have been moved downwardly into and through the normally curved flexible resilient drill guide 19 which will be held against movement therewith by virtue of its frictional engagement with the side walls of an existing well bore. Thus, when the clutch elements 35 and 36 are in the position shown in Figure 2, rotation of the drill string, including the lower portion of the lower section 10 thereof, together with the flexible drill string section 12, the coupling member 16 and the flexible drive member 17, will cause positive rotation of the bit 18 when the latter is being forced against the side wall of the existing vertical well bore 11 due to the pressure imposed thereon through the flexing of the drill guide 19 to a lesser curvature than that normally to be assumed thereby.

It will be observed that a downward pull on the flexible resilient drill guide 19 will tend to move the clutch teeth 35 and 36 into engagement, i. e., toward the position illustrated in Figure 3. The weight of the flexible resilient drill guide 19 and its associated annular bearing members 26 and 32 has been found to be so great that in the absence of means affirmatively holding the clutch teeth 35 and 36 in disengaged position, there is a tendency for the clutch to close and thereby bring about unwanted rotation of the flexible normally curved resilient drill guide 19. To avoid this undesirable tendency of the clutch teeth to close, there is provided, pursuant to the present invention and as illustrated in Figures 2 and 3, a

compression spring 37, the upper end of which bears against the annular member 32 and the lower end of which bears against a pressure ring 38 that rides on ball bearings 39 carried in a ball race 40 of an annular member 41 fixedly secured to the flexible non-resilient drive member 17. The arrangement is such that the bearings 39 preclude transmission of the frictional resistance imposed by compression spring 37 to the normally rotating flexible tubular drive member 17. It will be observed that the compression spring 37 is effective to force the annular member 32 and consequently the upper end of the flexible resilient drill guide 19 upwardly to thereby keep the clutch tooth 35 out of engagement with clutch tooth 36.

Now, assuming it is desired to orient the flexible normally curved resilient drill guide 19 so as to drill a lateral bore deviating from the vertical bore in a different azimuth, the drill string, including the lower portion 10 of the lower section thereof will be raised at the surface of the well and this will elevate the tubular coupling member 16 and elongate the hollow sectional flexible drive member 17 with respect to the resilient normally curved guide 19 which, it is noted, will be held against substantial axial movement by frictional engagement with the well bore so as to effect closing of the clutch and inter-engagement of the clutch teeth 35 and 36. It will be understood that during elevation of the drill string, slow partial rotation should be simultaneously effected to the end that clutch tooth 35 will be moved out of axial alignment with clutch tooth 36 and thereby permit their direct engagement. In Figure 3 the spring 37 is shown in its compressed condition which it assumes when the coupling member 16 moves upwardly elongating the hollow sectional drive member 17 with respect to the curved resilient guide 19. It will be noted that the bearing member 32 carried at the upper end of the curved resilient drill guide 19 is provided with a sufficient vertical extension to compensate for the required relative movement of member 32 and coupling member 16 to permit opening and closing of the clutch, i. e., engagement and disengagement of the clutch teeth 35 and 36 while retaining the ball bearings 34 in place.

In the operation of the combination unit conforming to the present invention, the upper end of the flexible non-resilient drill string section 12 is threaded onto the lower end 10 of the lowermost section of a conventional rotary drill string. The entire unit is lowered into the well into the zone of the producing formation where the drilling of a deviating bore is desired. The drill string is then slightly elevated to insure inter-engagement of the clutch teeth 35 and 36 and the drill string is then given a partial rotation requisite to impart desired orientation to the normally curved flexible drill guide 19. When the drill guide 19 has been appropriately oriented, the drill string is again lowered, the lowering of the drill string being sufficient to insure disengagement of the clutch teeth 35 and 36, whereupon rotation of the drill string is commenced, which effects a positive drive of the bit 18 which, under the pressure imposed due to the flexing of the curved resilient drill guide 19 initiates and continues to drill a lateral bore deviating from the existing vertical well bore.

While I have illustrated the interpositioning of anti-friction bearings to the flexible non-resilient driving member 17 and the flexible resilient

normally curved drill guide 19, it is to be understood that where drilling is effected through the employment of an oil or other lubricating base medium as the circulating drilling fluid, the parts of the assembly embraced by the present invention will be self-lubricated and friction thereby minimized to such an extent that the anti-friction means may be dispensed with. Thus, while employment of anti-friction means is illustrated in the exemplified embodiment, the inclusion of such illustration is not to be regarded as a limitation upon the invention.

Having thus described my invention, what I claim is:

15. In apparatus for drilling a lateral bore deviating from an existing vertical well bore, a resilient, normally curved, tubular drill guide which must be forcibly flexed from its normally curved configuration to enter an existing well bore, the resiliency of said drill guide when so flexed being adequate to store sufficient potential energy to forcibly guide a rotating drill bit in a path to drill a lateral bore deviating from the existing vertical well bore, a flexible, non-resilient, bit driving member extending through and rotatable within said drill guide, a flexible, non-resilient drill string section secured to the upper end of said flexible bit driving member, said drill string section and said bit driving member each comprising a plurality of generally tubular rigid elements interconnected in end to end relationship for relative angular movement with adjacent elements having longitudinally extending intermeshing teeth thereon for transmitting torque from element to element thereof, a drill bit secured to the lower end of said bit driving member for rotation therewith, and means for securing the upper end of said drill string section to the lower end of a rigid rotary drill string for rotation in unison therewith.
20. Apparatus as defined in claim 1 having means for effecting angular orientation of said normally curved tubular drill guide, said orienting means comprising a clutch operative, when engaged, to cause said normally curved drill guide to rotate with said flexible drill string section and said flexible bit driving member.
25. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
30. Apparatus for drilling a curved bore deflecting from an existing bore, said apparatus comprising a normally curved, flexible, resilient, deflector tube, a drilling bit rotatably mounted at the lower end of said deflector tube, a flexible drive member rotatable within said deflector tube and having its lower end connected to said drilling bit to rotate the same upon rotation of said drive member, said drive member comprising a plurality of tubular sections joined at their ends by loosely intermeshing and interlocking teeth thus permitting variations in the length of said drive member, means for securing a drill pipe to the upper end of said drive member, and a clutch between said drive member and said deflector tube operable, when engaged, to cause said deflector tube to rotate during rotation of said drive member, said clutch being arranged to engage upon elongation of said drive member as a result
35. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
40. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
45. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
50. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
55. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
60. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
65. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
70. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.
75. Apparatus as defined in claim 1 having means for effecting angular orientation of said normally curved tubular drill guide, said orienting means comprising a clutch, and a spring member biasing said clutch toward disengaged condition, said clutch being operative, when engaged, to cause said normally curved drill guide to rotate with said flexible drill string section and said flexible bit driving member.

of upward movement of said drill pipe relative to said deflector pipe and to disengage upon shortening of said drive member as a result of downward movement of said drill pipe relative to said deflector pipe.

5. Apparatus as defined in claim 4 in which a flexible hose extends through the interior of said drive member for conveying mud from a drill pipe to said drilling bit.

6. Apparatus as defined in claim 4 in which 10 said clutch is a toothed clutch comprising a single downwardly extending tooth secured to said deflector pipe and a single upwardly extending tooth secured to said drive member, said teeth

being complementary in form to mesh in one position only of relative rotational adjustment of said drive member and said deflector pipe.
